UNITED STATES PATENT OFFICE.

HAROLD S. BLACK, OF EAST ORANGE, NEW JERSEY, ASSIGNOR TO WESTERN ELECTRIC COMPANY, INCORPORATED, OF NEW YORK, N. Y., A CORPORATION OF NEW YORK.

MODULATED-CARRIER-WAVE SIGNALING SYSTEM.

Application filed September 26, 1925. Serial No. 58,744.

This invention is related to modulated carrier wave signaling systems, and to space discharge modulators, oscillators, and combination oscillator-modulators adapted to be used therein.

Although the invention may perhaps be most usefully employed in line-wire carrier wave systems the principles are applicable to carrier wave systems generally, including systems for signaling by radiant energy. A two-way circuit, that is, the minimum prerequisite for conversation, will be assumed as the practical signaling unit, the term "channel" being used to indicate one of such units.

Until recently the development of single channel modulated carrier wave signaling systems has been prejudiced by the fact that such a system has commonly been found to require the use of circuits and apparatus that could be used in common for a plurality of such systems, that is, multi-channel systems have been justly regarded as inherently more economical of plant.

It is an object of this invention to make the economy and other advantages of modulated carrier wave signaling systems generally realizable in smaller units than has heretofore been possible and specifically to provide a single channel modulated carrier wave signaling system in which the efficiency of operation, first cost, simplicity, stability, etc., approximates that of an equivalent single channel circuit comprised within a multi-channel modulated carrier wave signaling system. The over-all performance of the system to be hereinafter disclosed compares favorably with physical circuits routed over short lengths of non-loaded open wire copper lines and maintenance has been reduced to a minimum.

A subsidiary object is to provide a system having the characteristics above indicated and which additionally is adaptable with relatively slight modifications to extension into a multi-channel system when traffic outgrows the limitations of single channel operation.

Modern transposition practice, in most circumstances, requires the operation of multi-channel systems on the group frequency basis, that is, an operation in which all the channels used for each direction respectively employ frequencies grouped to-

gether. In other words, the groups of frequencies occupy a space in the frequency spectrum individual to their direction of transmission and distinct from that used for transmission in the opposite direction. Such a system is described in U. S. Patent 1,548, 55 260, August 4, 1923, to Espenschied. A single channel system adaptable to extension into such a multi-channel system must accordingly use different frequencies for opposite directions of transmission. In its 60 simplest conception it must have circuits at a terminal station individual to the two one-way portions comprising a complete single channel two-way system, each such portion utilizing the carrier frequency individual 65 thereto.

One way to secure economy in the use of material and of energy in such a system is to transmit a pure modulated wave in each direction. An effective way of accomplishing this is by suppressing the unmodulated carrier by a balanced circuit including space discharge modulating devices.

A still further way of promoting economy in the system, so far described, is to operate 80 each discharge circuit to effect modulation and also as an oscillator, that is, to use a self-oscillatory balanced modulator. Since a local receiver source must be used at each terminal, in the absence of a transmitted unmodulated carrier, the demodulator may similarly be made self-oscillatory to avoid the necessity of using a separate source supplying oscillations of carrier frequency, and it may be of the balanced type to suppress 85 the locally produced carrier. The resultant receiving circuit at each terminal is accordingly similar in structure and, in a broad sense, in function, to the corresponding transmitting circuit.

The type of single channel system characterized by the above described features is the invention of others. The present invention, although related to features that may be usefully employed in systems generally 100 employing oscillators, self-oscillatory modulators, and balanced self-oscillatory-modulators, is an improvement over such type of single channel system whether used alone or as a component unit of a multi-channel system into which it may be extended.

A specific object of the invention is to improve the frequency stability of a space dis-

charge circuit as affected by space battery potential variations.

This object is achieved in part by inserting a resistance in the grid-filament circuit of each space discharge device. When the grids become positive, as they must by reason of the feed-back that is necessarily incidental to the oscillating operation, rectified current will flow through this resistance, the average value of which will determine the average resultant negative bias which is added to the biasing potential impressed upon the grids by a separate polarizing source. The amount of feed-back is adjusted so that this additional bias so occurs as to compensate for exceptionally wide variations in the source of potential of the space current.

A further object is to improve such a system by eliminating the separate grid polarizing source altogether, that is, to rely upon the negative bias furnished by a grid stabilizing resistance, and to accomplish this result consistently with frequency stabilization.

This result, or these results, is, or are, achieved by increasing the amount of feed-back so that the grids are normally made positive once in each cycle, so that a normal negative biasing potential is applied to the grids.

Besides the increase of frequency stability resulting from the arrangement described above, it has been found that the stability of the system is increased in other ways. One measure of the efficient operation of a modulation system, or of its stability, is the constancy of the modulator gain irrespective of variations of the signal input, of the space battery potential, of the filament current, and also of variations in all elements comprising the circuit with the single exception of the frequency determining circuit. Further, frequency stability is affected, in addition to the effect of variation of space-battery potential, by variation of modulation input and filament current. It has been found that the arrangement of the invention insures a remarkable degree of stability, as affected by each of these factors. This result follows from the fact that each of them affects, in some way, the amplitude of the resultant potential impressed on the input circuit from the feed-back circuit, or from the external, modulating circuit, and thus the stabilizing operation is responsive to this resultant potential.

The remarkable stability that has been realized in practice may be illustrated by mentioning that, in the case of the first of the circuits to be disclosed in detail further on; if the "B" battery voltage is reduced from 150 volts to 18 volts, the frequency of the oscillations only changes by a small fraction of one percent.

For the particular case where the cathodes of the modulator or demodulator are in series with respect to a common source the resulting tendency toward dissymmetrical operation may be compensated by the use of individual grid resistances for the two tubes. However, it has been found that if a single resistance is used in a circuit common to the grid-cathode circuits of the two devices, while symmetry of operation is sacrificed, the same ultimate result is achieved. With weak input current levels only one of the space discharge devices, the one having the smaller negative biasing potential, cooperates with the resistance to perform the stabilizing and biasing functions for both devices. Any dissimilarity of the resultant output currents of the two devices, as to either amplitude or phase, can be corrected by impedance loading in the anode lead of one device. In general it is preferable to correct dissymmetry in this manner than to accomplish it by changing the arrangement of the grid circuits.

Additional features closely related to the resistance biasing means comprise:

1. The use of a very large biasing resistance, that is, of the order of infinity, the feed-back being adjusted accordingly. It has been found that this arrangement serves to increase the stability of the system, since the operation of the system is not affected by variations of the grid-cathode characteristic, or by those of the biasing resistance itself.

2. Means to insure efficient plate modulation, and to prevent, or to render innocuous, grid modulation; which tends to occur due to the operation of the grid biasing means, and which would be highly detrimental to the efficient operation of the circuit as a plate modulator.

In the preceding description the terms "modulation" and "demodulator" are frequently used. It is to be understood that these and similar terms, as so used and as they will be used throughout the specification and claims, except where another meaning is indicated by the context, comprehend the so-called "demodulation" operation and the "demodulator", since the operation of the two devices, considered qualitatively, is essentially the same.

Other objects and features of the invention and its principles of operation will be clearly understood from the following detailed description when read in connection with the accompanying drawing in which:

Fig. 1 illustrates the circuits constituting one embodiment of the invention;

Figs. 2 and 3 are graphical devices that are aids to the understanding of the operation of the invention; and

Fig. 4 illustrates the circuits constituting another embodiment of the invention,

In the description which follows the elements of the system will be identified so far as practically possible by literal designations which are suggestive of their respective functions.

Fig. 1 illustrates the circuits at one terminal of a modulated carrier current system of the invention, which is also composited so as not to interfere with or limit in any manner, the use of terminal apparatus for the transmission of voice frequency or telegraph signals or the association of phantom circuits with the transmission circuit 2. Compositing is accomplished by what is commonly denominated a "carrier composite set" comprising a low pass filter FLP in the low frequency circuit 1 and the high pass filter FHP in the high frequency circuit. The high and low frequency circuits are connected to the transmission circuit 2, the high frequency circuit by means of transformer 3, which may be replaced if desired by a conductive connection.

The filters FLP and FHP effectively separate the currents corresponding to the frequencies used in the respective types of transmission. Obviously, the system could be used for modulated carrier wave transmission alone, in which case these filters could be dispensed with. When used in this manner, the transmission circuit 2 could be, or could be connected with, a radio antenna, to adapt the system for radio signaling. As modified to permit the transmission of low frequency, of course the circuit 2 would have the form of the usual conductive connection between communicating stations.

The circuits, adapted for the superimposed modulated carrier wave transmission, constitute the necessary elements whereby two-way communication may be accomplished between low frequency circuit 4, which may be connected, for example, with a central office of the usual telephone system, and the transmission circuit 2.

The transmitting portion of this two-way circuit comprises the following elements which function in like sequence; low frequency line 4, balanced oscillator-modulator BOM, output transformer 5, transmitting band filter FTB, high pass filter FHP, transformer 3, and transmission circuit 2. This portion of the apparatus operates as follows: The low frequency modulating current in line 4 is intermodulated with a carrier current in the device BOM which constitutes a unitary self-oscillating balanced-modulator, and the proper resultant modulated currents are selected by filter FTB and transmitted through filter FHP and transformer 3, whose functions have been described above, to the transmission circuit.

The portion of the two-way circuits adapted for receiving comprises the following elements which function in like se-

quence; transmission circuit 2, transformer 3, high pass filter FHP, receiving band pass filter FRB, transformer 6, balanced-oscillator-demodulator BODM, output transformer 7, low pass filter FLP₁ and low frequency circuit 4. The operation of this portion of the two-way apparatus is as follows: The modulated carrier side bands incoming from transmission circuit 2 are transferred by the transformer 3 and selected by filter FHP from undesired currents, including the low frequency telephone currents transmitted over the circuit 2, transmitted through receiving band pass filter FRB which further discriminates against currents having undesired frequencies and furthermore insures that transmitted modulated carrier current may not enter the receiving circuits, and through transformer 6 to device BODM in which the modulated carrier side bands are combined with oscillations produced on account of the self oscillating character of the device to reproduce, by a demodulating operation, the modulating current transmitted from the distant communicating station. This demodulated current is then transmitted through transformer 7 and low pass filter FLP₁ to the low frequency line 4. Filter FLP₁ insures that the only current transmitted therethrough is such demodulated current, that is, it separates this current from certain high frequency currents whose production is incidental to the demodulating operation.

Circuit N is a network designed to balance low frequency line 4. This network, the low frequency line 4, and the transmitting and receiving low frequency circuit are connected in energy transfer relation through hybrid coil or balanced transformer 8 in such a manner as to conjugately connect the transmitting and receiving circuits to the low frequency line. The function of this hybrid coil and the specific circuit for carrying it out are illustrated conventionally. They are sufficiently well understood by those skilled in the art as to require no further description.

Selection, rather than balance, is relied on at the junctions of the high frequency portions of the transmitting and receiving circuits to prevent interference therebetween. This is made possible by proper choice of different frequencies for the two directions of carrier transmission. The use of different carrier frequencies for the two directions of transmission in the single channel circuit described makes it possible, without change of frequency or of the interconnected circuits including the filters, to extend the system into a desirable type of multi-channel system, that is, a multi-channel system whose frequencies are arranged on a group basis.

In the single channel system described,

5 economy in the use of material and economy
6 of energy used is effected by the use of the
7 balanced-oscillator-modulator and balanced-
8 oscillator-demodulator, since the use of these
9 devices in the circuit avoids the necessity of
10 using oscillator circuits distinct from the
11 modulator and demodulator circuits, and in-
12 sures that the output wave is pure, that is,
13 contains no unmodulated carrier component.

14 The particular circuit features which
15 characterize the system of the invention con-
16 stitute elements in such balanced-oscillator-
17 modulators and balanced-oscillator-demodu-
18 lators or their immediately associated cir-
19 cuits. Their presence results in a marked
20 improvement, over prior circuits, of stabil-
21 ity of frequency and of modulator gain as
22 effected by, for example, space battery po-
23 tential variation, variation of signal input,
24 and variation of filament current. The de-
25 scription from this point will be confined to
26 the details of these two circuits, the bal-
27 anced-oscillator-modulator and the bal-
28 anced-oscillator-demodulator.

29 The common translating circuit BOM, used to operate as an oscillator and as a
30 balanced modulator, or in other words, as a balanced self-oscillatory-modulator, com-
31 prises a balanced circuit including two elec-
32 tric discharge tubes 9 and 10 which may be
33 of the usual three-electrode type, including
34 a cathode, an anode, and a control electrode
35 or grid. The cathodes of these tubes are
36 connected serially and in series with the
37 similarly related cathodes of the electric
38 discharge tubes of the balanced-oscillator-
39 demodulator BODM by means of circuit 11
40 and ground. The cathodes of the two tubes
41 are so related to source 12 that the cathode
42 of tube 9 is adjacent the negative end of such
43 source, whereby the average potential of this
44 cathode is lower than that of the cathode of
45 tube 10.

46 The junction point of the cathodes of tubes
47 9 and 10 is connected to the mid-point of
48 the secondary of the input transformer or
49 hydrid coil 8, the grids of the two tubes
50 being connected to the respective opposite
51 terminals of the secondary by conductors 13
52 and 14. The same point in the cathode cir-
53 circuit is also connected through tuned feed-
54 back circuit 15, feed-back resistance 16, and
55 blocking condenser 17, to the mid-point of
56 the primary of output transformer 5 and
57 thence through the two halves 18 and 19 of
58 this transformer to the anodes of the respec-
59 tive tubes.

60 Space current is supplied to these anodes
61 from direct current source 20, through choke
62 coil 21 and the two halves 18 and 19 of the
63 primary of transformer 5. Condenser 17 and
64 choke coil 21 insure that the space cur-
65 rent and the high frequency feed-back cur-
66 rent are confined to their individual paths.

67 The common portion of the grid-cathode cir-

68 cuits of the two tubes contains secondary
69 winding 22, which couples the tuned cir-
70 circuit 15 to this common portion. Resistances
71 23 and 24 are connected across the two halves
72 of the secondary winding of the input trans-
73 former 8 so as to provide a sufficiently high
74 stable impedance for the input circuits of
75 the two tubes. The use of impedances in
76 this relation conduces to an efficient opera-
77 tion of the two tubes as translating devices. 78

79 The grids of the two tubes are given a
80 proper fixed negative bias by means of large
81 resistances 25 and 26 each of which is made
82 individual to the grid of one of the two
83 tubes by means of blocking condensers 84
84 27 and 28. The use of this type of bias-
85 ing means, and its function in stabilizing
86 the operation of these circuits is an impor-
87 tant feature of the invention and will be
88 considered separately later. Resistance 29,
89 which is connected across the tuned circuit
90 15 and feed-back resistance 16, contributes
91 further to the efficient operation of the out-
92 put circuits. Its specific manner of accom-
93 plishing this will be described later. 94

95 It is a necessary characteristic of a proper-
96 ly balanced circuit of the type illustrated
97 in this figure that the output circuit, con-
98 nected to the secondary of output trans-
99 former 5, and the input circuit, connected
100 to the primary winding of transformer 8,
101 should be balanced with respect to voltages
102 applied through the feed-back circuit to the
103 common portion of the grid-cathode circuits
104 of the tubes. This is accomplished by virtue
105 of a certain relation of the windings of the
106 several transformers. For example, the two
107 halves 18 and 19 of the primary of trans-
108 former 5 should be wound in the same direc-
109 tion with respect to their common axis. A
110 similar relation applies to the primary and
111 secondary of transformer 8. However, the
112 voltage variations impressed on the common
113 portion of the grid-cathode circuits are re-
114 peated in amplified form in the two anode
115 branches of the output circuit, which in-
116 cludes the common portion, comprising tuned
117 circuit 15, and the portions of the output
118 circuit individual to the two anodes. By
119 tuning the circuit 15 to the desired fre-
120 quency, the circuit as a whole may therefore
121 be caused to oscillate independently at this
122 frequency, since the output energy in the
123 tuned circuit is returned in part to the input
124 circuits where it is again amplified. Since
125 the path which the oscillations follow is
126 neutral with respect to the input and output
127 circuits connected to transformers 5 and 8,
128 the locally generated oscillations are confined
129 to the translating circuits, and are therefore
130 prevented from passing into either of the
131 input and output circuits coupled to the
132 translating circuits by the transformers 5
133 and 8.

134 The operation of the translating circuit 135

as a modulator will be clear from the following description of the path taken by currents in the course of translation with relation to the path of the oscillating current.

5 Modulating current from low frequency circuit 4 flows through on the primary winding of transformer 8 and, on account of the connection of its secondary winding to the grids of devices 9 and 10, causes the potentials of the grids to vary in an opposite manner to produce complementary impedance variations in the anode-cathode paths of these tubes. In this manner, the translating circuit is unbalanced to an extent dependent 10 on the amplitude of the impressed potentials and the modulating current is accordingly transmitted to the output circuit, connected to the secondary transformer 5, as variations in the amplitude of the high frequency current produced by the oscillatory action of the translating devices. The high frequency carrier currents themselves are balanced out so that they do not appear in such output circuit.

20 25 The operation of the circuit as a modulator, as thus far described, is similar to that disclosed in U. S. patent to Carson 1,343,306, June 15, 1920, to which reference is made for a more complete description. It will be recognized after reading this patent and the remainder of the present specification that other arrangements of transformer windings and of the input and output circuit with respect to the circuits more immediately associated with the tubes, may equally well be used in the system of the present invention.

30 35 It is a characteristic of modulating circuits generally, including the balanced-modulator illustrated in Fig. 1, that for efficient operation the external path of the output circuit must have an impedance at the desired output frequencies which is substantially equal to the impedance of the space current path within the devices. This is accomplished by proper design of the output transformer 5. It is also required, for efficient operation, that the output circuit have small or zero impedance at the two impressed frequencies, that is, the carrier and the modulating frequencies. The balanced relation 40 45 of the output transformer of Fig. 1 insures that such output circuit will have a very low effective impedance for the carrier frequency. Additional means for insuring a very low impedance for the carrier frequency is provided by the resistance 29 which is connected in shunt to the feed-back circuit in the common portion of the anode-cathode circuits of the two tubes. The use of this 50 55 resistance with the balanced relation of the winding of the output transformer insures that every part of the circuit, as a whole through which carrier frequency current tends to flow has a very low effective impedance at the carrier frequency.

60 Although the amplified modulating current flows in such directions through the windings 18 and 19 of the output transformer as not to make the balanced relation effective in the same manner for these currents, nevertheless, low impedance is insured by a design of the transformer, since a design which is of high impedance for the side bands is consistent with a low impedance for the modulating currents. In this connection 70 75 it is necessary to design the filter FTB so that its impedance across the terminals, connected to transformer 5, is substantially zero for all frequencies lying within the band comprising the modulating current. 80

85 The function of the grid resistances 25 and 26 may be best explained with reference to Fig. 2. In this figure curves *a* and *b* are respectively the well known grid-potential-space-current and grid-potential-grid-current characteristics of a typical space discharge tube, adapted to be used in the circuit of Fig. 1. These curves are plotted with reference to the intersection of the coordinate axes, indicated at "O". It is desired 90 to operate the tubes at a substantially constant negative grid potential corresponding to the potential E_g . The shaded areas associated with the carrier voltage curve indicate quantitatively the variations of the grid potential that are effective in varying the electron emission from cathode to grid. The fixed negative bias results from the fact that when the grids are periodically made positive by the energy fed back to coil 22 100 through tuned circuit 15, current flows from the grids to the cathodes, or, which is the same thing, negative electrons pass from the cathodes to the grids. This current which is indicated by I_g plotted on a time axis near the lower right-hand corner of the figure flows impulsively, since the grids can become positive only during the positive alternations of the current fed-back. The ordinates of 105 110 this grid current curve are greatly exaggerated as compared with the corresponding values taken from curve *b*.

115 Obviously this curve I_g also indicates the character of the compensating currents flowing in the grid circuit. It may be considered as made up of a direct current component on which is superposed alternating current. The direct current component determines the fixed negative bias. If desired a levelling condenser may be placed around each of the 120 grid biasing resistances to further accentuate the value of the direct current as compared with the superposed alternating current component.

125 Individual resistances are used, instead of a single resistance in the common grid-cathode lead, for the reason that the "free" grid potentials tend to be different for the two tubes by reason of the fact that the cathodes are in series with each other, with 130

reference to the energizing source 12, as explained above. This means that different values of resistance must be used for the respective grid circuits. The coupling between the feed-back circuit 15 and coil 22 is adjusted, with the shunting resistance 29 in the circuit, so that with very large grid resistances, there will be sufficient feed-back to produce the desired fixed negative biasing potentials. The resistances may then be adjusted relatively to each other and the feed-back coupling and shunting resistance readjusted until there is an exact balance consistently with the desired biasing potentials.

The advantages accruing from the use of very large grid resistances is illustrated in Fig. 3 in which the curve discloses the relation, for any particular value of feed-back potential, between the grid resistance and the resultant grid biasing potential. The curve is in no sense quantitative since the scale of ordinates depends altogether on the value, for example, of the feed-back potentials. The figure is intended to illustrate only the variation characteristic with changes in grid resistance. It shows that for a resistance approaching infinity, the curve is nearly horizontal. This means that variations of this grid resistance, or of the grid-cathode characteristic which effectively forms a part of it, have relatively slight effect when a resistance of approximately infinite value is used. Obviously, the stability of the system is increased by using a resistance of that value.

In addition to the functions described above, the grid resistances also serve to compensate for effects which tend to produce changes in the amplitude of the resultant potential impressed on the grids, whether due to the feed-back circuit or the modulating wave circuit. That is, they compensate for changes in input potential, changes in potential of the source 20, and changes in cathode current and also prevent variations in frequency and gain that would otherwise attend such changes. For example, consider the effect of change in potential of source 20. An increase of the potential of this source causes the circuit to oscillate more violently and therefore to correspondingly increase the feed-back potential and hence the resultant potential on the grids. The effect is exaggerated where an air core coupling transformer, instead of an iron core transformer, is used in the feed-back circuit, since this type of core does not have the storage characteristics that an iron core transformer has. The use of an air core transformer has certain advantages in the system described, including that of low cost and an impedance which does not vary with changing temperature, which would in certain circumstances determine its use as a standard element in

such a system. The biasing potential correspondingly becomes more negative and therefore tends to oppose the tendency to such increase in violence of oscillation. Since the frequency and gain of the tubes 70 as translating devices have a direct relation to the degree of violence of the oscillations, the resultant effect is to stabilize these quantities, that is, to prevent them from changing.

The function of stabilizing the system may be made independent of the function of negative grid biasing. For example, the amount of feed-back may be adjusted so that grid current normally does not flow, but 80 flows only when the potential of the space source 20 increases above normal. For this alternative operation a separate normal negative grid biasing source may be used.

The structure and characteristic modes of 85 operation of the transmitting portion of the two-way circuits at the terminal station illustrated in Fig. 1 have been described above. The structure and mode of operation of the receiving portion of the channel illustrated in the lower part of the figure is similar. In fact, the continuity may be, as it is in the instance illustrated by Fig. 1, identical. The mode of operation is also identical in its theoretical aspects the only difference being in the numerical values of the 90 quantities involved. For instance, in the modulator, the waves impressed, that is, the modulating and carrier waves, have radically different frequency values, and the resultant 100 side bands have frequency values comparable with that of the carrier, whereas, in the case of the demodulator, the waves impressed upon it, namely, the side bands and local oscillations have frequencies of the same 105 order, and the resultant low frequency demodulated wave has a frequency of a radically different order.

The description of the balanced-oscillator-modulator will be understood to apply with 110 in these limits to the circuits of the balanced-oscillator-demodulator, which is therefore shown largely without reference numerals.

The condenser 30 is related in identical manner with the modulator and the demodulator, and is necessary only because a common anode source, which necessarily must contain some impedance, is used for both devices. Its purpose is to insure that the total impedance in the circuit of this source 115 is at all times negligible. The ultimate result is to prevent the modulator and demodulator reacting upon one another, which would otherwise be caused by the variable drop across the impedance contained in the 120 circuit of the common space source.

Fig. 4 illustrates an alternative circuit differing from that of Fig. 1 in certain elements. The elements which are similar in structure and function to those of Fig. 1 are 125

similarly labeled, but only those elements which are different will be described in detail.

This circuit illustrates a simplified form of the circuit of Fig. 1 in that it makes use of a single grid biasing and stabilizing resistance 31 placed in the common portion of the grid-cathode circuits of the two tubes, instead of a resistance individual to each tube included in its input circuit. Most of the differences in operation of the two circuits result from the use of this feature. For example, with this arrangement of grid-cathode circuits, since the cathodes are in series with each other, and with the energizing source as in Fig. 1, the "free" potentials of the grids of the two tubes with respect to their individual cathodes, that is, the potential independent of any biasing potential resulting from the use of the resistance 31, will differ by an amount corresponding to the drop across one cathode. This dissymmetry with respect to the plate-filament circuits is exaggerated by an amount corresponding to the amplification constant of the tube. The use of a single biasing resistance therefore tends to result in a dissymmetrical operation of the tubes. In a particular practical arrangement, this difference in the grid potentials was found to amount to about 4 volts. In general, it is so great that when the feed-back potential is so adjusted as to provide a steady negative biasing potential for tube 9 through the operation of the biasing resistance 31, the grid of tube 10, when there is no signal current supplied to the input circuit, fails to become positive at any point on the cycle of the feed-back potential. This means that the tube 9 performs the biasing and stabilizing function for both tubes, so far as it is determined by the biasing resistance 31. As compared with tube 10 the steady negative biasing of tube 9 is a composite of the biasing determined by the resistance 31 and the biasing determined by the potential across its cathode. The tube 9 therefore functions in the conventional manner of self-excited oscillators, whereas tube 10 functions as a hybrid oscillator and amplifier, or perhaps better stated, as a non-oscillatory regenerative, or separately excited amplifier.

The expedient of using a single biasing resistance is in the direction of economy of plant and simplicity of circuit. The resulting dissymmetry does not affect the ultimate result, since it does not detract from the value of the circuit as a means for suppressing or balancing out the unmodulated carrier component although it may result in a slight difference of phase or amplitude, or both, of the output currents flowing through coils 18 and 19. This is compensated by the resistance-inductance combination 32 in the anode lead of one of the tubes.

Since, in this figure, the biasing resistance is in the common lead through which the current due to feed-back connection flows, provision must be made to insure that the impedance of the input circuit for the current fed-back is not too great. This is accomplished by connecting in shunt to the biasing resistance a condenser 33 having low impedance at the frequency of the oscillations generated. This condenser also functions to improve the operation of the resistance by levelling the impulsive current flowing therethrough. It will be charged at the potential impressed across the combination during each alternation when the grid becomes positive. Its capacity must not be too great or it will not have time to discharge through the very high resistance 31 during the negative alternation. The time of this discharge is determined by the product of its capacity and the value of the biasing resistance. On the other hand, the capacity must not be too small or it will unwarrantably impede the carrier current. In practice it has been found possible to choose a value of capacity which meets both of these conditions.

When the grid periodically becomes positive the conditions in the input circuit are favorable to grid current modulation. This form of modulation results from the non-rectilinearity of the grid-potential-grid-current characteristic instead of the grid-potential-anode-current characteristic. The non-rectilinearity results from the relatively great change of impedance when the grid becomes positive. The theory of this type of modulation as distinguished from plate current modulation, which is the much more usual form, is described in British Patent 247,626, April 14, 1926. Since plate current modulation is relied upon in this instance, grid current modulation is detrimental, inasmuch as when the modulated products resulting from grid modulation have been amplified and appear in the external plate circuits of the tubes, they are in phase opposition to the otherwise similar side bands resulting from plate current modulation. Grid current modulation in the circuit of Fig. 4 is substantially prevented, or at least so reduced that its effect is made negligible by the insertion of condenser 34 between the grids of the two tubes. This condenser provides a low impedance path between the points at which the side bands resulting from grid current modulation tend to occur and therefore prevents the potentials of such side bands from reaching a value which would materially reduce the amplitude of the side bands resulting from plate current modulation.

In Fig. 4, the stabilizing input resistance 35 is shown connected between the two grids. As a practical matter, it is immaterial

whether this arrangement or the arrangement involving resistances 23 and 24 of Fig. 1 is used.

The receiving circuits are related to high and low frequency transmission circuits 2 and 4 in the same manner as in Fig. 1. The only feature therein which has not been already sufficiently described in connection with Fig. 1 is the use of tuned circuits 36 and 37 in the feed-back circuits of the two tubes. These circuits are for the purpose of providing a low impedance path for the side band frequencies impressed on the demodulator. It has been shown above that efficient 15 operation of a modulator (of course the principle is equally true of a demodulator) requires that the output circuit have a low impedance at each of the impressed frequencies. In the case of the modulator, the 20 output transformer and associated band filter are carefully and purposely adjusted so that the output circuit has high impedance at the side band frequencies and a very low impedance for the modulating frequencies. However, in the case of the 25 demodulator the output transformer, which must have high impedance for the demodulated low frequencies, would have a very much higher impedance for the impressed 30 side bands, regardless of the impedance of filter FLP, at these frequencies, so that a separate circuit means must be employed to provide a low impedance path therefor. The functions of the circuits 36 and 37 are 35 described in an article by J. R. Carson, published in the Proceedings of the A. I. E. E. for June, 1921, the only difference being that this publication describes the effect of making the output impedance low for the impressed carrier, instead of the impressed 40 signal wave, the theoretical principle being identically the same.

These tuned circuits have an additional function which is specific to an arrangement, 45 of which the circuit of Fig. 4 is an example, in which a perfection of balance of circuits arranged in push-pull relation cannot be completely secured. This function is not suggested in the Carson application. It may 50 be explained as follows:

As has been described the efficient operation of modulators (including demodulators) requires, among other things, that the output circuit have low or zero impedance 55 at the carrier frequency. Incidentally also in an oscillator, and therefore in an oscillator-modulator, the amplitude of the oscillations is great in proportion as a low impedance path is provided for the oscillation 60 currents. It has also been explained that, on account of the series relation of cathodes and common sources, the two tubes function somewhat differently so as to tend to produce a slight dissymmetry in the output 65 circuits of the two tubes. To the extent that

there is such dissymmetry, the balanced relation of output circuits does not, as it otherwise would, effectively provide a zero impedance path in the individual plate filament circuits of the two tubes. The tuned 70 circuits provide a low impedance path for the carrier currents and accordingly ameliorate the condition resulting from such dissymmetry. The tuned circuits are obviously properly located to permit this function to be 75 effected, since each of them provides a direct path from the plate of one of the tubes to the oscillation circuit.

In a limiting case the connection from the junction of these tuned circuits to the transformer 7, which now includes condenser 38, may be omitted altogether, the tuned circuits alone being relied on to provide the low impedance paths. In order that these 80 tuned circuits can perform their function 85 with respect to the carrier frequency consistently with their somewhat similar function with respect to the received side bands a compromise tuning may be adopted, that is, the circuits may be tuned to a frequency 90 at or near the inner edges of the side bands. Obviously separate tuned circuits may be used, one set tuned to the carrier and the other to the side band frequencies. Consistently with the function of these tuned 95 circuits to compensate for an unbalance or dissymmetry of the output circuits, each of them should be entirely independent of the other, that is, there should be no mutual impedance therebetween. 100

Although the general plan of the invention has been described above, there are certain additional aspects of it that need treatment. It should first be noticed that there is no feed-back resistance in the circuit of Fig. 105

4. This can be explained as follows:

Although a method has been described, in connection with Fig. 4, for decreasing the effects of grid modulation, or for decreasing the relative amount of grid modulation, obviously a complementary method of decreasing the relative amount of grid modulation is by increasing the amount of plate modulation as by providing a low impedance path 110 for the carrier frequency. As has been described this may be done by balancing the individual portions of the plate-cathode circuits and decreasing the impedance of the common portion as much as possible. In the system of Fig. 1 the impedance of the common portions of the circuits was made low 115 by means of resistance 29 and the requisite stability was secured by the use of the resistance in the grid-cathode circuits and by the use of a feed-back resistance. 120

In the system of Fig. 4 an equivalent ultimate result is secured without the use of the shunting resistance 29 or the feed-back resistance and, further, with decreased cost 125 of the oscillation circuit. 130

This result is accomplished in part by making the inductance in this oscillation circuit very low and the capacity very high. Thus the impedance of this circuit to carrier frequency is very much less than if the inductance were large and the capacity were small, assuming in each case the presence of a small amount of resistance. This may be expressed in the language of circuit design by saying that it results in making the "Q" of both the inductance and capacity, and accordingly the "Q" of the combination, small. This means that the impedance is small. The specific design of the feed-back circuit will be considered later. As a practical matter the impedance can be made small as compared with the joint plate resistance of the two tubes in parallel, and small enough to obviate the necessity for the shunting resistance 29 of Fig. 1. Additional advantages of this arrangement are that the load carrying capacity of the circuit is increased, its design is greatly simplified and its cost is materially reduced. When to these advantages there is added those resulting from the elimination of the feed-back resistance, the efficiency, load carrying capacity and economy are correspondingly still further increased. To overcome any attendant loss of stability the stabilizing resistance is made extra large. Accordingly the stabilizing resistance in Fig. 4 tends to be larger than either of the stabilizing resistances in Fig. 1. It is, especially, because of the very great stabilizing resistance used in Fig. 4 that the shunting condenser 33 is required to by-pass the high frequency carrier currents.

The elimination of the feed-back resistance and the particular design of the oscillation circuit as described is a radical departure from conventional practice, which requires an oscillation circuit of very high impedance and a large feed-back resistance.

In addition to increasing the stability, as in the manner pointed out immediately above, by compensating for the effects caused by the omission of the feed-back resistance, and in the manner pointed out with reference to Fig. 3, the use of a very large stabilizing resistance has a pronounced effect in decreasing grid modulation. That it has this result is evident when it is considered that with an infinite biasing resistance the grids cannot be made to go positive, so that there can be no grid modulation. In a practical case the resistance would be made so great that the grid current flowing would be reduced a negligible value and hence be insufficient to cause an appreciable amount of modulation in the grid-circuit.

An interesting feature of the system of either Fig. 1 or Fig. 4 is the use of a normal biasing potential having a much greater negative value than is customary in conventional practice. This is disclosed in Fig. 2.

As a matter of practice a normal negative biasing potential to give the self-oscillatory circuits of Figs. 1 and 4 a maximum frequency stability, using a grid biasing resistance, was found to be about 9 volts. The negative bias necessary in order to secure optimum modulator operating characteristics was found to be about 27.5 volts. What was actually done was simply to choose a value of negative bias highly satisfactory from the standpoint of modulation and then to increase the biasing resistance to restore the oscillator stability.

In this connection it was found that the stability of frequency, stability of gain, and load carrying capacity were enormously increased if a voltage as great as 60 was used, instead of 27.5. The value of stabilizing resistance for the conjunction of conditions just described is consistent with its value as governed by the more or less independent considerations stated in the preceding paragraphs.

In order to further teach a person skilled in the art to build a circuit possessing the characteristics of the oscillator-modulator circuit of Fig. 4 the following data is taken from a circuit which was used under practical operating conditions:

The inductance of the feed-back coil (the primary of the feed-back transformer) is 314 micro-henries. Its resistance is .34 ohms.

The quantity $\frac{L\omega}{R}$ for this coil, known by designers of this type of circuit as the "Q" of the coil 59.5. The inductance of the secondary of the feed-back transformer is 39.15 mil-henries. The coefficient of coupling is 89.5%. The voltage step-up is 10. The capacity of the tuning condenser of the feed-back circuit is .757 micro-farads. The "Q" of the condenser ($= \frac{1}{CR\omega}$) is 150. The stabilizing resistance is of the order of 4 meg-ohms. The capacity of the condenser shunting the stabilizing resistance is .001 micro-farads. The tubes used are known in the trade as 101-D tubes. The average amplification constant μ of such a tube is 5.8. Its plate resistance R_p under operating conditions is 7500 ohms. The static characteristic of such a tube is indicated by the equation

$$i_b = \epsilon \cdot 1.86 \log e_b - 6.09$$

in which e_b is plate voltage, i_b is space current in mils and ϵ is the base of the natural system of logarithms. The design constants of the corresponding oscillator-demodulator are readily derivable from the above values and from the known differences in the frequencies concerned in the operation of the two devices. From the general principles governing the design of the circuit of Fig. 1 as outlined above, similar design constants may be deduced therefor.

While the invention has been illustrated as embodied in a limited number of forms, it will be understood that it is equally well adapted to other forms and may embody 5 variations in details, without departing from the spirit of the invention as defined in the appended claims.

The principle governing the advantage of the use of very large biasing resistances that 10 is illustrated by Fig. 3 and described with reference to the system of Fig. 1 is also applicable to the system of Fig. 4 to the extent that it illustrates the shape of the portion of curve corresponding to the large 15 resistances that would be used in practice. However, the portion of the curve corresponding to the lower value of grid resistance for the system of Fig. 4 is quite radically different from that shown, since there- 20 in the asymptotic approach to the horizontal proceeds from a maximum point higher than the finally attained value of biasing potential if the resistance is increased to infinity.

What is claimed is:

25 1. The method of stabilizing the operation of a space discharge translating device having a cathode, a space discharge path, an input electrode, and means for energizing said cathode and space discharge path, as af- 30 fected by abnormal changes in condition of said elements and abnormal changes in the impressed variations, which comprises feeding back a portion of the translated elec- 35 trical variations from said discharge path to the input electrode and utilizing said varia- 40 tions to vary the normally fixed negative potential applied to said electrode in proportion to the change from normal in the amplitude of the variations impressed on said

45 2. The method of operating a space dis- charge translating device, having a cathode, a space discharge path, an impedance con- 50 trol electrode, and means for energizing said cathode and discharge path, to produce a normal negative bias for said electrode which varies so as to stabilize the operation of the device, as affected by abnormal changes in the condition of said elements and by abnor- 55 mal changes of the impressed variations, which comprises feeding back a portion of the translated electrical variations from said discharge path to the control electrode and utilizing said variations to impress upon 60 said electrode a normal negative biasing potential which varies proportionally to the amplitude of the variations impressed thereon.

65 3. The method of operating a space dis- charge oscillator having an input circuit in- 60 cluding a control electrode which comprises utilizing the variations fed back to impress on said control electrode a potential which varies in proportion to the change in the am- 70 plitude from normal of said fed-back varia-

tions, whereby the operation of the oscillator is stabilized with respect to those variations of the characteristics of the electrical element comprising the oscillator which tend to produce variations in the amplitude of the 70 oscillations.

4. The method of operating a space dis- charge oscillator having an input circuit in- 75 cluding a control electrode which comprises utilizing the variations fed back to the input circuit to impress on said control electrode a normal negative bias which varies proportionally with the amplitude of the fed-back variations.

5. The method of operating a space dis- charge self-oscillatory modulator having an 80 input circuit, including a control electrode and an output circuit, which comprises utilizing variations impressed on said control elec- 85 trode, including the modulating variations and the fed-back variations, to vary the normally fixed potential of said electrode nega- 90 tively in proportion to the amplitude of the waves so impressed, whereby the operation of said device is stabilized with respect to those 95 variations of the characteristics of the electrical elements comprising the modulator which tend to produce abnormal variations of the impressed wave.

6. The method recited in claim 5 in which 95 the impressed variations are utilized additionally to produce the normal negative bias of the control electrode.

7. In combination a space discharge trans- 100 lating device having a control electrode and a cathode, means whereby the control elec- 105 trode periodically becomes positive with respect to said cathode when the translated current increases above normal and in proportion to said increase, and a circuit in- cluding a resistance connecting said control electrode and said cathode and through which current is adapted to flow from said cathode to said control electrode to compensate for the accumulated negative charge on 110 said control electrode, whereby said control electrode is given an increment of negative potential bias proportional to the increase of translated current above normal.

8. The combination recited in claim 7 in- 115 cluding additionally a condenser in shunt with said resistance, whereby the flow of current through said resistance tends to be more nearly constant.

9. In combination a self-oscillatory mod- 120 ulator comprising an oscillatory circuit, a space discharge tube including an anode and cathode and an impedance varying electrode, means for impressing modulating waves on said cathode and impedance vary- 125 ing electrode, a resistance connecting said cathode and impedance varying electrode, and means whereby, due to the control elec- 130 trode periodically becoming positive with respect to said cathode when the amplitude

of the resultant impressed waves including the oscillation component increases above normal, said control electrode is given an increment of negative bias proportional to 5 the amplitude of such impressed waves.

10. The combination recited in claim 9, including additionally a condenser connected in shunt to said resistance.

11. The combination recited in claim 9 in 10 which the last mentioned means is adjusted so that said control electrode periodically becomes positive during the normal as well as abnormal operation of the circuit, whereby said control electrode is given a normal 15 negative bias which is adapted to increase proportionally with the increase in amplitude of the impressed waves.

12. The combination recited in claim 9 in which the last mentioned means is adjusted 20 so that said control electrode periodically becomes positive during the normal as well as abnormal operation of the circuit, whereby said control electrode is given a normal negative bias which increases proportionally with the increase in amplitude 25 of the impressed waves, and a condenser connected in shunt to said resistance.

13. In combination a pair of space discharge translating devices, each having a 30 cathode, an anode, and a control electrode, a circuit including an energizing source connecting said cathodes in series, an input circuit connecting the cathode and control electrode of each device, an output circuit 35 connecting the cathode and anode of each device, a feed back circuit containing frequency determining elements connecting the output circuits collectively with the input circuits collectively, and an individual 40 circuit including a resistance, connecting the control electrode of each device to its cathode, the values of said resistances with relation to the feed back adjustment being such that the control electrodes periodically 45 go positive when the amplitude of the waves impressed on the input circuits, including the feed-back wave, increases beyond normal, by equal amounts and by amounts proportional to such increase in amplitude.

50. 14. The combination specified in claim 13, including additionally means for impressing modulating waves on said input circuits.

15. The combination specified in claim 13 in which the resistances and the feed back 55 are so adjusted that the control electrodes periodically go positive during normal operation of the circuit by an amount sufficient to provide a desired, substantially equal, normal negative bias for said control electrodes.

60. 16. The combination specified in claim 13, including means for impressing modulating waves on said input circuits and in which further the resistances and feed back are so 65 adjusted that the control electrodes peri-

odically go positive during normal operation of the circuit by an amount sufficient to provide a desired, substantially equal, normal negative biasing potential for the said control electrodes.

70

17. The combination specified in claim 13, including a circuit for impressing modulating waves on said input circuits, and an independent circuit for deriving resultant carrier modulated waves from said output circuits, said input, output and feed back circuits being in balanced relation to each other and to said independent output circuit so that when no modulating waves are being impressed no current flows in said independent circuit.

75

18. The combination specified in claim 13 in which the resistances and the feed back are so adjusted that the control electrodes periodically go positive during normal operation of the circuit by an amount sufficient to provide desired, substantially equal, normal negative biasing potentials for the said control electrodes, and including a circuit for impressing modulating waves on said 85 input circuit and an independent circuit for deriving modulated carrier waves, said input, output and feed back circuits being in balanced relation to each other and to said independent output circuit so that when no 90 modulating waves are being impressed no current flows in said independent circuit.

95

19. In combination a pair of space discharge translating devices, each having an input and an output circuit, the output circuits, including a common portion, a feed back circuit containing frequency determining elements connecting the output circuits collectively with the input circuits collectively, a circuit for impressing modulating 100 waves on said input circuits, an independent circuit for deriving modulated carrier waves from said output circuits, said input, output and feed back circuits being in balanced relation to each other and to said independent circuit so that when no modulating waves are being impressed no current flows in 105 said independent circuit, and a relatively low impedance in shunt with said feed back circuit, thereby a low impedance path is offered to the carrier frequency, as required for efficient modulation.

110

20. In combination, a pair of space discharge translating devices, each having a cathode, an anode, and a control electrode, a circuit including an energizing source connecting said cathodes in series, input circuits connecting the cathodes and control electrodes of the pair of devices and including a common portion and a portion individual 115 to each control electrode, output circuits associating the cathodes and anodes of the pair of devices, an independent circuit for deriving energy from said output circuits, and a feed back circuit containing frequency de- 120

125

130

termining elements connecting said output circuits collectively with the common portion of said input circuits and a resistance in the common portion of the input circuits, 5 the value of said resistance with relation to the feed back being such that the control electrode of one of the devices periodically goes positive when the amplitude of the waves impressed on the input circuits, 10 including the feed-back waves, increases beyond normal, by an amount proportional to the increase in the amplitude of said impressed waves.

21. The combination specified in claim 20 15 in which the resistance and feed back are so adjusted that the control electrode of one device periodically goes positive during normal operation of the circuit by an amount sufficient to provide a normal negative bias 20 for both devices, one different from the other by the potential drop across one cathode.

22. The combination specified in claim 20 25 in which the resistance is between substantially four megohms and infinity.

23. The combination specified in claim 20 including means for impressing a modulating current on said input circuits.

24. The combination specified in claim 20 30 including means for impressing modulating waves on said input circuits, said input, output and feed back circuits being in balanced relation to each other and to said independent circuit so that when no modulating wave is being impressed no current flows in said independent circuit.

25. In combination a pair of space discharge translating devices, each having a cathode, an anode and a control electrode, 10 a circuit including an energizing source connecting said cathodes in series, input circuits associating the cathodes and control electrodes of the pair of devices and including a common portion and a portion individual to each control electrode, output circuits associating the cathodes and anodes of the pair of devices and including a common portion and a portion individual to each anode, an independent circuit for deriving energy from 15 said output circuits, means for impressing modulating waves on said input circuits, a feed back circuit containing frequency determining elements connecting said common portions of the output and input circuits, a resistance in said feed back circuit, impedance means in the individual portion of at least one output circuit, said input, output and feed back circuits, and said impedance means being in balanced relation 20 to each other and to said independent circuit so that when no modulating wave is being impressed no current flows in said independent circuit, and the value of said resistance, with relation to the feed back adjustment being such that a change of the 25

amplitude of the resultant waves impressed on the input circuits, produces a proportional change in the resultant positive potential impressed on the control electrode of at least one of the devices and therefore produces a proportional change in the negative bias potentials applied to the control electrodes of both devices.

26. The combination recited in claim 25, 30 including a condenser connected across the control electrodes of the two devices and adapted to constitute a low impedance path therebetween for the side bands produced by grid modulation, whereby the production of said side bands in the output circuit is materially reduced.

27. The combination recited in claim 7 35 in which said resistance has a value of the order of infinity.

28. In combination a modulator, comprising a space discharge tube, an input path, and an output path, means for impressing modulating currents and carrier currents together on said input path, means for deriving the resultant modulated products from the output path, means whereby the input path becomes periodically conductive, means cooperating with said first means and including a resistance connected in shunt to said input path to normally render said input path non-conducting and means for substantially preventing the production of modulation products by grid current modulation as affected by the operation of the first two mentioned means.

29. The combination recited in claim 28 40 in which the last recited means comprises a condenser, having low impedance to the frequencies, due to grid current modulation, connected across said input path.

30. In combination, a pair of space discharge translating devices, each having a cathode, anode, and a control electrode, energizing means for said cathodes, input circuits associating the cathodes and control electrodes of the pair of devices and including a common portion and a portion individual to each anode, an independent circuit for deriving energy from said output circuits, a feed back circuit including frequency determining elements connecting said output and input circuits, means for impressing modulating currents on the input circuits of said devices, means producing dissymmetry of the currents in the individual portions of said output circuits when no modulating currents are impressed, said individual portions of said output circuits being arranged in push-pull relation with said independent circuit and said output circuits being proportioned relatively to said independent circuit so as to 45

efficiently transduce the resultant low frequency modulated products, and an additional circuit having low impedance at the frequency determined by said feed back circuit connecting the cathode and anode of each device, whereby the output circuits have low impedance for the unbalance currents resulting from said dissymmetry.

31. The combination cited in claim 30, in which the common portion of the input circuits contains a resistance and in which the means for producing dissymmetry is a series connection of said cathodes and the energizing means, said resistance and the feed back being so adjusted that the control electrode of one device periodically goes positive during normal operation of the circuit an amount sufficient to produce a normal negative bias for both devices, one differing from the other by the potential drop across one cathode, and which varies proportionally to the amplitude of the variations impressed on said input circuit.

32. An oscillation-generator comprising an electric discharge device, including an input circuit and an output circuit, a feed back circuit connecting said input and output circuits and having an impedance at the oscillation frequency which is small as compared with the impedance of said output circuit and means for stabilizing the frequency of said oscillation-generator to compensate for the inherent loss of stability resulting from the low feed back impedance.

33. The combination recited in claim 32, in which the feed back circuit consists substantially wholly of a tuned circuit connected in antiresonant relation therein, the "Q's" of whose inductance and capacity are so small that the antiresonant impedance of the tuned circuit at the oscillation frequency is small as compared with the impedance of the internal output circuit of the device.

34. The combination specified in claim 32, in which the feed back circuit consists substantially wholly of a tuned circuit connected in antiresonant relation therein, the "Q" of whose inductance and capacity is so small that the antiresonant impedance of the tuned circuit at the oscillation frequency is small as compared with the impedance of the internal output circuit of the device, and a resistance connected across the internal input circuit of said device having such value as to stabilize the oscillation frequency.

35. In combination, a pair of space discharge translating devices each having a cathode, an anode and a control electrode, a circuit including an energizing source connecting said cathodes in series, an input circuit connecting the cathode and control electrode of each device, a means for impressing potentials on said input circuits collectively, an output circuit connecting the cathode

and anode of each device, and an individual circuit including a resistance, connecting the control electrode of each device to its cathode, the values of said resistances with relation to the related circuits being such that the control electrodes periodically go positive, when the amplitude of the waves impressed on the input circuits increases beyond normal, by equal amounts and by amounts proportional to such increase in amplitude.

36. The combination specified in claim 35 in which the resistances are so adjusted that the control electrodes periodically go positive during normal operation of the circuit by an amount sufficient to provide a desired, substantially equal, normal negative bias for said control electrodes.

37. In combination, a pair of space discharge translating devices, each having a cathode, an anode and a control electrode, input circuits connecting the cathodes and control electrodes of the pair of devices and including a common portion and a portion individual to each control electrode, output circuits associating the cathodes and anodes of the pair of devices, an independent circuit for deriving energy from said output circuits, and a resistance in the common portion of the input circuit, the value of said resistance with relation to the feed back being such that the control electrode of at least one of the devices periodically goes positive when the amplitude of the waves impressed on the input circuits increases beyond normal, by an amount proportional to the increase in the amplitude of said impressed waves.

38. The combination specified in claim 37 in which the resistance is so adjusted that the control electrode of at least one device goes positive during normal operation of the circuit by an amount sufficient to provide a normal negative bias for both devices.

39. In a demodulator, a pair of space discharge devices connected in push-pull relation, a low frequency divided output winding connected to the output electrodes of said devices, a circuit for supplying space current for said devices connected to the output circuits of said devices, a high-frequency by-pass connected from a point between the sections of said output winding and one of the output electrodes of each of said devices, and means cooperating with said by-pass forming high-frequency paths between the output electrodes of each device in shunt to both sections of said winding.

40. In a demodulator, a pair of space discharge devices connected in push-pull relation, a low frequency divided output winding having portions individual to the output circuits of said devices, a circuit for supplying space current connected between the out-

put electrodes of said devices, a high-frequency path connected between the same output electrodes that are connected to the outermost terminals of said output winding, a high-frequency path from a point within said first path to the other output electrodes of said devices, and a high-frequency path

connected from a point between the portions of said output winding and a point in said first path.

In witness whereof, I hereunto subscribe my name this 24th day of September, A. D., 1925.

HAROLD S. BLACK.
